UNITED STATES PATENT OFFICE.

WILLIAM J. PANNIER, JR., OF PITTSBURGH, PENNSYLVANIA, ASSIGNOR TO PANNIER BROTHERS STAMP COMPANY, OF PITTSBURGH, PENNSYLVANIA, A CORPORATION OF PENNSYLVANIA.

STAMP.

071,527.

Specification of Letters Patent.

Patented Aug. 26, 1913.

Application filed October 15, 1912 Serial No. 725,838.

To all whom it may concern:

Be it known that I, WILLIAM J. PANNIER, Jr., a citizen of the United States, residing at Pittsburgh, in the county of Allegheny and State of Pennsylvania, have invented 5 certain new and useful Improvements in Stamps, of which the following is a specification.

My invention is an improvement in the 10 class of stamps, similar to rubber stamps, and adapted to mark any suitable surface with an imprint by means of raised letters extending beyond a supporting base or surface.

15 The invention has in view to provide a stamp of this character, either for hand use or mechanical application by rolls, in connection with a suitable inking pad or medium.

20 One of the principal objects of the invention is to provide a stamping element or die which may be attached to and used with a suitable supporting base, preferably resilient, whereby to avoid the necessity of providing such base for each particular 25 stamp. Ordinarily, such stamps are made by molding the letters or characters in rubber on a printing portion which is permanently mounted and connected with the 30 cushion, which in turn is affixed to the stamping handle or frame, the several parts forming inseparable portions of each stamping unit. This practice, especially 35 with stamps or rubber dies of large size, involves very considerable expense and storage room, which is avoided by my improvement.

The present invention comprises a supporting frame or holder having a resilient 10 cushion portion, arranged in the arc of a circle around its under face and adapted to receive and hold, with sufficient tension to maintain it in position, an operable web-like printing or stamping member, the 15 frame having devices for stretching such member across the face of the cushion and fixedly holding it thereon, constructed and adapted to operate in the manner more fully hereinafter described.

50 Referring to the drawings, figure 1 is a view in side elevation illustrating one preferred form of the invention. Fig. 2 is an under plan view of the device of Fig. 1. Fig. 3 is an enlarged detail view in plan,

showing a portion of the adjusting mechanism. Fig. 4 is a sectional detail view taken on the line IV. IV. of Fig. 3. Fig. 5 is a similar view taken on the line V. V. of Fig. 3. Fig. 6 is a perspective detail view illustrating a portion of the printing and stamping member, partly broken away. Fig. 7 is a view in side elevation illustrating the application of the invention to two supporting rollers, arranged for double stamping. Fig. 8 is an enlarged detail view, showing one of such rollers provided with adjusting devices for each end of the stamping member.

Referring to the hand operated machine, illustrated on sheet 1 of the drawings, it 70 comprises a light portable frame of the desired size, preferably made of sheet metal having end portions 2, 2, connected by a back 3 and a bottom portion 4. These parts are arranged, as illustrated, for stiffness 75 and convenience in use, and are provided with gripping handles 5, 5, one at each end, carried by the outwardly projecting brackets 6, 6, respectively. The bottom 4 extends around underneath from one of the 80 end portions 2 to the other in the arc of a circle, of suitable radius to facilitate the rolling operation of the stamp, from one end to the other, over the surface being marked. Upon the under side of the bottom 4 is cemented, or otherwise suitably secured, a resilient pad 7 of sponge cushion or other suitable material, the outer surface of which is curved in parallelism with the base 4 and presents a smooth continuously 85 curved supporting face for the stamping element from one end to the other.

At each end the main frame is provided with a projecting ledge or flange 8, 8, which may be conveniently made by extending 95 the end 2 in the manner shown, and redoubling it, as indicated at 9, for insuring strength and stiffness for the attaching and adjusting devices.

The printing element consists of a strip 100 10 of webbing, canvas, or other suitable material with which is incorporated the rubber base 11 having the projecting integral rubber stamping characters 12, formed by molding, as is well understood. The purpose of incorporating the web backing 10 with the rubber strip 11 is to give the entire stamping member sufficient strength so

that it may be stretched taut over the curved cushion 7 without undue stretching, by thus reinforcing the rubber, and to also provide against ordinary wear and tear. Each end 5 of the stamping member is provided with a metallic terminal 13, of thin sheet metal, for substantially the full width of the stamping member at each end, said terminal being permanently connected with the 10 stamping member by molding it therewith, or otherwise connecting these parts in any suitable way. In the construction shown, the sheet metal terminal 13 is provided at its inner portion with a plurality of closely 15 adjacent openings 14 and intervening connecting portions 15, the rubber strip 11 being integrally formed through the openings 14 and at each side of the sheet metal, as clearly illustrated in Fig. 6, by which means 20 the parts are permanently connected. It will be understood, of course, that the terminal 13 may be otherwise secured or attached, if desired, as by riveting or sewing, for the same purpose.

25 The terminal 13 is provided with a series of longitudinal slots 16 which extend outwardly for substantially the full width of the exposed portion of the terminal, and then inwardly at right angles to its main 30 body portion centrally through corresponding inwardly bent retaining lugs or lips 17, as indicated at 16'. Mounted transversely across the bottom 4 of the frame at one or both ends is a tightening bar 18. In the hand machine, I ordinarily utilize but one such tightening bar, due to the fact that the extent of curvature of the frame is not sufficient to prevent ample tightening from one end only. At 0 the tightening end of the frame, in such case, I provide an adjusting screw 19, 19, one for each corner or side of the base, extending through and rotatable in suitable 5 openings in the reinforced lip 9, each provided with a thumb terminal 20, 20. The bar 18 is correspondingly threaded, engaging the screws 19, and said screws at their other ends pass through up-turned lips or lugs 21, 21, formed of the sheet metal of the bottom 4, by punching it upwardly therefrom, in the manner clearly illustrated in Figs. 3 and 4.

The inner ends of belts 19 are provided with a terminal bearing nut or collar 22 with a tightening set nut, cotter pin, or other suitable device. The bar 18 is provided across its outer face with a plurality of pins 23 and along its outer edge with a corresponding plurality of pins 24. The purpose of pins 23 is to facilitate the alignment and adjustment of the terminal 13 in applying it to the bar by engaging slots 16, and of pins 24 to positively engage the slots 16', and to retain the terminal 13 in holding engagement with the bar 18, in ad-

dition to the engagement with the bar itself by the right angle lips 17.

The terminal 13 at the other end of the stamping member is of the same construction and, in the hand machine, is ordinarily hooked over the reinforced lip 9, which is also provided with a series of pins 25, positively engaging the slots 16' and retaining that end of the stamping member. 20

For the purpose of facilitating the operation of the adjusting screws 19, the bottom 4 is preferably made straight for a short portion of its length, as indicated at 4' (see Figs. 4 and 5), thus providing a flat surface over which the bar 18 may move in parallelism with the adjusting screws 19. 75 80

The hand grips 5 are preferably of the construction shown in the drawings, consisting of cylindrical-shaped handles rotatably mounted on centralizing pins carried at each end in the bracket extension 6. The operation of the gripping device 10 is as follows:

The operation of the invention will be readily understood from the foregoing description. When any particular stamping member is to be used, it is merely slipped over the lip 8 and into engagement with pins 25 at one end of the frame, laid across the cushion 7, the other terminal 13 brought down over the bar 18 with the slots registering with the pins 23 and 24, and the bar 18 is then tightened by the screws until the printing element or strip is drawn taut across the cushion. The frame is then grasped by the handles 5, one in each hand, and the printing strip is inked by a partial rolling operation over a suitable inking pad, when the impression is then made on the surface to be marked, in the same manner.

The curved surface of the device greatly facilitates the marking operation, enabling ample pressure to be exerted throughout the entire length of the stamp, insuring regularity of impression and great speed. 105

When it is desired to use the invention in combination with supporting rollers, for the purpose of stamping two or more colors, two or more rollers 26 may be provided in the manner illustrated in Figs. 7 and 8. In such case the stamping elements or strips are provided with letters or characters which co-operate to form the entire stamped subject-matter, the rollers being so arranged that the stamping portion of one will properly interfit and combine with that of the other, each receiving its proper amount of ink from any suitable source, as inking rollers 27, 27. In such case, the stamping strip 11' is made in all respects substantially similar to that just described, except that it is provided at each end with adjusting screws 19', 19', positively engaging adjusting bars 18', 18', each of which effects a stretching adjustment of the strip at each end. Such arrangement is preferable because of the fact that the placing of the 130

strip around a suitable portion of the drum or wheel results in considerable additional friction, which is readily overcome by tightening from each end. In such arrangement the article being stamped, as a box 28, is fed along underneath the rollers upon any suitable surface 29, receiving an imprint from each roller successively, suitable feed mechanism, gearing, etc. to effect the proper 10 operation of the machine being provided.

The advantages of my invention will be readily appreciated by all those familiar with this class of stamps. It facilitates the stamping operation; it obviates the necessity 15 of keeping on hand a large number of stamping bases, each having its particular stamp; it effects great economy in storage space of the several stamping elements; it is rapid and effective in changing the stamping strips; and, on account of the curved 20 surface, it greatly simplifies and facilitates the use of the device by the workman.

It will be understood that the invention may be greatly changed or varied in details 25 of construction, design, proportion, etc. by the skilled mechanic, but that all such changes are to be considered as within the scope of the following claims.

What I claim is:

30 1. In a stamp of the class described, the combination of a rigid holding frame having an outer curved face, a fixedly attached projecting resilient cushion thereon having an outer conformably curved face, a flexible 35 stamping die consisting of a strip of rubber having projecting integral stamping elements, sheet metal holding and clamping portions associated with the flexible stamping die and extending beyond each end 40 thereof, and means on the holding frame for engaging the terminal ends of said portions and tightening the die over the cushion, substantially as set forth.

2. A stamp consisting of a rigid holding 45 frame having an outer curved face, a fixedly attached projecting cushion thereon having an outer conformably curved face, a flexible stamping die of reinforced rubber laid over said cushion and provided with metallic 50 terminals, and means on the holding frame for engaging said terminals and tightening the die over the cushion, substantially as set forth.

3. The combination of a rigid holding 55 frame having an outer curved face, gripping handles extending from each end portion of the frame, a curved projecting cushion thereon, holding devices embodying tightening mechanism projecting from the frame longitudinally beyond the cushion at each end 60 thereof, and a flexible stamping die laid over said cushion and engaging said holding devices by its end portions, substantially as set forth.

65 4. The combination with a holding frame

having a curved bottom provided with terminal securing flanges, a supporting cushion, and a tightening bar, of a flexible stamping die laid over the cushion having terminal clips engaging one of said flanges and said tightening bar respectively, and adjusting screws engaging the other of said flanges and said tightening bar, substantially as set forth. 70

5. In a stamp of the class described, a holding frame of sheet metal having terminal handles, a curved bottom, a curved cushion projecting therefrom, terminal lips extending beyond the bottom at each end, one of said lips having pins and the other having adjusting screws, an adjusting bar engaging said screws, and a flexible stamping die laid over said cushion having terminals adapted to engage one of said terminal lips and said bar respectively, substantially as 85 set forth.

6. In a stamp of the class described, a holding frame of sheet metal having terminal handles, a curved bottom, a curved cushion projecting therefrom, terminal lips extending beyond the bottom at each end, one of said lips having pins and the other having adjusting screws, an adjusting bar engaging said screws and provided with pins, and a flexible stamping die laid over said cushion having slotted metallic terminals 90 adapted to engage one of said terminal lips and said bar and the pins thereon, substantially as set forth. 95

7. The combination of a supporting frame having a curved bottom, a fixedly attached projecting cushion thereon having an outer curved face parallel with the face of the bottom, projections extending outwardly beyond the bottom surface beyond each terminal end of the cushion, a flexible stamping die laid over the cushion, and means for connecting the ends of the die with the projections and for tightening it over the cushion, substantially as set forth. 100

8. The combination of a supporting frame having a curved bottom, a fixedly attached projecting cushion thereon having an outer curved face parallel with the face of the bottom, projections extending outwardly beyond the bottom surface beyond each terminal end of the cushion, a flexible stamping die laid over the cushion having a securing terminal at one end engaging the projection at one end of the cushion, a securing terminal at the other end, and tightening devices connecting said terminal with the other projection, substantially as set forth. 115

9. The combination of a supporting frame having a curved bottom, end portions and a top of sheet metal, gripping handles secured to the end portions, a curved cushion extending beyond the bottom, a flexible stamping element laid over the cushion, and means securing each end of the stamping element to 120 125 130

the frame beyond the ends of the cushion and embodying tightening devices, substantially as set forth.

10. In a stamp of the class described, the combination of a supporting frame having a top, end portions, gripping handles extending therefrom, a curved rolling bottom, a conformably curved elastic cushion extending along and outwardly from the bottom, a flexible stamping die laid over the curved cushion, and mechanism for holding the die tightly over the curved cushion embodying quickly operable connections with

the supporting frame, said die having projecting stamping portions extending circumferentially beyond said connections whereby to facilitate application of the stamping portions to a surface and avoid interference therewith by such connections, substantially as set forth.

In testimony whereof I hereunto affix my signature in the presence of two witnesses.

WILLIAM J. PANNIER, Jr.
